UNITED STATES PATENT OFFICE.

WILLIAM N. PARKES, OF BROOKLYN, NEW YORK.

EMBROIDERY FOR FINISHING THE EDGES OF FABRICS.

Application filed February 25, 1919, Serial No. 279,094. Renewed October 11, 1923.

To all whom it may concern:

Be it known that I, WILLIAM N. PARKES, a citizen of the United States, residing in the borough of Brooklyn, in the county of Kings and State of New York, have invented new and useful Improvements in Embroidery for Finishing the Edges of Fabrics, of which the following is a specification.

10 This invention relates to the construction, and method of constructing scallop embroidery along the edge or edges of fabric, or articles. It has for its main object the construction of scallop embroidery so the 15 inner stitches of the embroidery are anchored in the fabric, and the outer stitches in scallop form off the edge or edges of the fabric, and the providing of means for holding the 20 stitches made off the edge of the fabric in scallop form.

The embroidery herein illustrated and described is essentially composed of stitches made with a sewing machine, but, preferably of zigzag stitches made with a lock 25 stitch zigzag sewing machine. To hold in position the stitches made off the edge of the fabric an auxiliary thread is preferably looped completely around each of the said 30 stitches.

In U. S. Patent 875,607 issued to applicant Dec. 31, 1907, is illustrated means for making zigzag stitches, and means in combination therewith for looping an auxiliary thread completely around each stitch of one 35 of the rows of stitches that a zigzag seam comprises. In U. S. Patent 875,625 also issued to applicant on Dec. 31, 1907, is illustrated means for making the zigzag 40 stitches, and for locating them in scallop design on the body of the fabric, or article, and in combination therewith means for looping an auxiliary thread around the 45 stitches along the outer edge of the scallops so as to form a button hole finish along said edge.

In my copending application, Serial No. 274,532 filed February 1st, 1919, is illustrated and described a sewing machine for making zigzag stitches, and means for use in 50 combination for automatically forming and locating these stitches in scallop embroidery along the edge of the fabric, with the stitches of the outer edge of the scallop embroidery located off the edge of the fabric, and means 55 for use in combination whereby an auxiliary

thread is looped around each stitch made along the outer edge of the embroidery.

It is the method of making the stitches of the outer edge of the scallop embroidery off the edge of the fabric, and of looping 60 an auxiliary thread around these said stitches to hold them in position, and the method of locating a filling material between the stitch connecting links of needle and bobbin thread, that constitutes my present invention. In connection with the filling material, however, it is noted that this is not essential to the invention as the auxiliary thread, as operated by the machine of my said copending application, holds in position 70 the stitches of the embroidery made off the edge of the fabric without the use of a filling material.

Fig. 1 is a diagrammatic top plan view illustrating how the auxiliary thread is looped around the stitches made along the outer edge of the embroidery, and Fig. 2 is a bottom view of Fig. 1. Fig. 3 is a view illustrating the auxiliary thread drawn sufficiently taut to form a button hole finish along the said outer edge of embroidery, and also sufficiently taut to hold the stitches along this edge in position.

In the drawings, 1 is the upper part of the fold of a strip of fabric, 2 the under part, 3 one edge of the strip, 4 the other edge, and 5 is the folded edge of the strip.

6 is the needle thread, 7 the bobbin thread, 8 the auxiliary thread, and 9 is a filling material which is located under the stitch 90 connecting links 10 of the needle thread, and 11 represents the stitch connecting links of bobbin thread.

All the inner stitches of the scallops are anchored in the fabric; these stitches are 95 designated by the reference character 12, except the stitch which is located opposite the apex of the arch of the scallop which stitch is designated by 13, and the stitch opposite the cusp of the scallop which is designated by 14.

All the outer stitches of the embroidery are designated by 15, except the stitches 16 and 17, which form the cusp of the scallops, and the stitches 18 and 19 which are located 105 to form the apex of the scallops.

In the making of the preferred form of the scalloped embroidered edge, the strip of fabric may be previously folded, or it may be folded by any suitable means as the 110

stitches of the embroidery are made. The basic stitches of the embroidery may be formed by looping the needle thread 6 around the bobbin thread 7, thereby forming the well known lock stitch, which is made by a lock stitch sewing machine.

The stitches may be held in place, and a button hole finish made along the outer edge of the embroidery by making the stitches 10 over a finger and by looping the auxiliary thread 8, around the stitch connecting links 10 of the needle thread, and then by drawing the auxiliary thread so that the said links of needle thread become twisted 15 around the auxiliary thread at the extreme outer edge of the scallops as illustrated and described in my before mentioned copending application.

The strip of fabric may be moved automatically to locate the stitches in the scallops, and the filling material 9 may be simultaneously therewith guided under the links of needle thread, as is also shown and described in the said copending application.

25 While applicant has herein illustrated the embroidery located along the folded edge of strips or pieces of fabric, it will of course be understood that it may also be made along the selvage edge or the raw edge of 30 a single thickness of fabric, but, it will be more firmly secured when located along the folded or the selvage edge. And while the basic stitches are of the kind made on zig-zag lock stitch machines applicant desires it 35 to be understood that his invention is not limited to the use of this particular kind of basic stitch.

In practice, in finishing the edge of fabrics or articles with the large size scallops, the 40 stitches 16 and 17 are made just inside the edge of the fabric, so that the stitches opposite the center of the arch of the scallops may be located securely in the edge of the fabric without having the embroidery of an 45 excessive width. These stitches when made in the edge of the fabric are covered by the button hole finish so that it does not show from the top or right side of the trimming that they are made in the edge of the fabric. 50 It is desired however that it be understood that in practice, when it is not desired to have any of the edge of the fabric on the underside of the work show outside the outer edge stitches of the embroidery, that 55 stitches 16 and 17, as well as all the other outer stitches of the embroidery are located off the edge of the fabric.

Applicant means, by the term "scallop embroidery" which is used herein, embroidery comprising concavo-convex shaped embroidered figures, or figures in the form of a segment of a circle. And the word "fabric" comprises fabric as a raw material, or fabrics partly or wholly made into an 60 article or articles of manufacture.

Having now described my invention what I claim as new is:

1. An edging for fabrics comprising a row of sewing machine stitches formed in the fabric, a row of sewing machine stitches 70 formed in a scallop design over and away from the edge of the fabric, the stitches formed over and away from the edge of the fabric connected with those formed in the fabric by connecting links of thread, the 75 said stitches and connecting links of thread located so that the connecting links of thread extend progressively step by step over and away from the edge of the fabric and thereby serve as a finish continuously along said edge, and an auxiliary thread looped around the said connecting links of thread along the outer edge of the said scallop design. 80

2. An edging for fabrics having a straight edge, said edging comprising zigzag sewing 85 machine stitches located along said edge, the stitches of the inner edge of said zigzag stitches formed in the fabric, the stitches of the outer edge of said zigzag stitches formed in a scallop design which extends 90 over and away from the edge of the fabric, and an auxiliary thread concatenated with the stitches formed over and away from the edge of the fabric.

3. An edging for fabrics comprising a 95 row of stitches formed in the fabric, stitches formed in a scallop design off the edge of the fabric, all of said stitches comprising a needle thread and a bobbin thread, the stitches formed off the edge of the fabric 100 connected with those formed in the fabric by stitch connecting links of needle and bobbin thread, and an auxiliary thread looped around the stitch connecting links of needle thread. 105

4. An edging for fabrics comprising a row of lock stitches formed in the fabric, a row of lock stitches formed in a scallop design off the edge of the fabric, the stitches formed off the edge connected with those 110 formed in the fabric by stitch connecting links of needle and bobbin thread, an auxiliary thread looped around the portions of the stitch connecting links of needle thread which are located off the edge of the fabric, 115 and a filling material located under said portions of stitch connecting links of needle thread.

5. An edging for fabrics comprising lock 120 stitch zigzag stitches located in scallops, the stitches of the inner edge of said scallops formed in the fabric, the stitches of the outer edge of said scallops formed off and away from the edge of the fabric, and an auxiliary thread concatenated with the 125 stitches which are formed off the edge of the fabric so as to hold said stitches in position in said scallops.

6. A scalloped edging for fabrics comprising a row of sewing machine lock 130

stitches anchored consecutively step by step in a scallop design in the fabric, a second row of sewing machine lock stitches anchored consecutively step by step in said scallop design over and away from the edge of the fabric, each of the stitches which are anchored over and away from the edge of the fabric connected consecutively by stitch connecting links of thread with the stitches which are anchored in the fabric, a filling material located under said stitch

connecting links of thread, and an auxiliary thread looped consecutively around each of the stitch connecting links of thread along the outer edge of said scalloped edging. 15

In testimony whereof I have signed my name in the presence of two subscribing witnesses.

WILLIAM N. PARKES.
